UNITED STATES PATENT OFFICE.

WALTER D. LEE, OF GRAND JUNCTION, COLORADO.

BRUSHING AND POLISHING MACHINE.

Application filed May 23, 1925. Serial No. 32,382.

This invention relates to a machine designed to brush and polish hard wood or waxed floors or other surfaces.

It is aimed to provide a novel construction which will effect a material saving in both time and labor and at the same time be exceedingly simple and capable of manufacture at low cost.

A particular object is to provide a construction having a novel sectional and removable arm which houses the intermediate driving parts and which journals and positions the shaft for the brushes.

Another object is to provide a construction which is adjustable at any desired angle according to the work.

Additional objects and advantages will become apparent from a consideration of the description following taken in connection with accompanying drawings illustrating an operative embodiment.

In said drawings:—

Figure 1 is a plan view of the device;

Figure 2 is a side elevation;

Figure 3 is a rear elevation;

Figure 4 is a sectional view taken on the line 4—4 of Figure 1 and passing longitudinally of the arm;

Figure 5 is a transverse sectional view taken on the line 5—5 of Figure 1 and passing transversely of the arm;

Figure 6 is a sectional view taken on the line 6—6 of Figure 1 and passing longitudinally of the motor shaft;

Figure 7 is a sectional view taken on the line 7—7 of Figure 1 passing particularly through the brush shaft at its connection with the arm; and Figure 8 is a detail view of one end of the brush shaft and hub.

In carrying out the invention, the operative parts are mounted upon a suitable truck as at 10 comprising a platform 11 mounted on rollers 12 and adapted to be controlled by a conventional removable handle 13 at the rear thereof.

Rigidly secured to the platform as by bolts 14 is a standard 15 which is bifurcated at its upper end to provide spaced bearings 16. A pulley 17 is journaled in the bearings 16 and 50 removably connected as by a set screw 18 to a drive shaft 19 which may be the main shaft of an electric motor 20, suitably supported on the platform 11 and adapted for connection to any suitable source of electric current. An endless drive belt 21 is trained over the pulley 17 particularly in a groove or

depression 22 thereof. Shaft 19 has a detachable connection with the motor so that the same with the pulley 22 in place thereon may be withdrawn through the bearings 16 in a direction away from the motor for the release or replacement of the belt 21.

Belt 21 is also trained over a pulley 23 as in a groove or depression 24 thereof. Pulley 23 is rigid with a brush shaft 25 and may be detachable therefrom if desired, for instance being fastened thereto by a set screw as at 26. Said shaft 25 carries suitable brushes 27, one on each side of the pulley 23, said brushes having hubs 28 of cylindrical form slidable over the shaft 25 and removably secured thereon by pins or keys 26 which pass through openings in the ends of shaft 25 and enter notches 29 in the outer ends of the hubs 28, whereby the hubs and brushes are connected to the shaft removably but against relative turning movement.

An arm structure is provided at 30 to house the driving connections and as well operatively mount the shaft 25 with respect to the standard 15 and shaft 19. This arm structure 30 consists of two substantially similar sections 31 separable from each other and detachably secured together as at 32 in any suitable manner. The arms 31 are hollow and at their ends are widened so as to have flanges at 33 and 34. The flanges 33 extend to the shaft 19 intimately fitting its exterior, and thus overlapping the bearings 16 and hub 17. Said hub 17 is grooved at 35 and has bearing balls or the like 36 disposed therein which also engage the flanges 33. By reason of these flanges 33 the bearing 16 and pulley 17 are held assembled with arm 30 on shaft 19. It will be understood that the end of the lower arm 31 adjacent to the shaft 19 is bifurcated to conform to the support or upright 15.

The flanges 34 intimately fit the periphery of the shaft 25 and thus overlap the ends of the pulley 24 and accordingly the arm 30 mounts the shaft 25 removably in place. The ends of pulley 24 are grooved as at 37 and have bearing balls disposed therein which also engage the flanges 34.

The arm structure 30 serves as a handle in the positioning or manipulation of the brushes as will be understood and such arm structure may be fastened at various angles according to the extent of engagement of the brush with respect to the floor, as by means of a set screw 39 carried by the upper-

most arm 31 and adapted for binding engagement against the adjacent bearing 16. Normally the set screw 39 is out of binding relation with the adjacent bearing 16 and hence the brushes are subject to free vertical movement to fluctuate with the undulations of the floor. Said brushes 27 may be of any type desired and depending upon the work, that is whether or not the floor is to be merely brushed or polished or is to be used in the application of a coating of wax or the equivalent thereto.

In use, the motor 20 under appropriate control, drives the shaft 19 and accordingly pulley 17 which in turn drives belt 21 and pulley 23, brush shaft 25 and the brushes 27. The brushes 27 thus rotate and due to their engagement with the floor accompanied by a movement of the platform 11 over the floor, polish the same in an obvious manner. The various parts may be disassembled for inspection, or repair, in the manner previously set forth.

Various changes may be resorted to provided they fall within the spirit and scope of the invention.

What is claimed is:—

1. A device of the class described comprising a brush shaft, a driving member rigid on said shaft, a supporting arm for said shaft, and said supporting arm overlapping said driving member at the ends thereof to prevent longitudinal displacement of the shaft, said supporting arm being in part separable to release the shaft with the brush assembled thereon, and driving means associated with said driving member.

2. A device of the class described comprising a brush shaft, a driving member rigid on said shaft, a supporting arm for said shaft, and said supporting arm overlapping said driving member at the ends thereof to prevent longitudinal displacement of the shaft, said arm being sectional with its parts removable in a direction transversely of the shaft to permit release of said shaft while the brushes are assembled thereon, and driving means for said member passing through said arm.

3. A device of the class described comprising a brush shaft, a pulley rigid on said shaft, a sectional arm carrying said shaft and having parts overlapping the ends of said pulley to prevent longitudinal displacement of the shaft, said parts being separable to release the shaft with the brushes assembled thereon, and driving means for said shaft including a flexible element passing through said arm and trained over said pulley.

4. A device of the class described comprising a single shaft, brushes removably disposed on said shaft, a driving member rigid on said shaft intermediate said brushes, supporting means for said shaft engaging opposite ends of said driving means to prevent displacement of the shaft, said supporting means being in sectional parts removable in a direction transversely of the shaft to release the shaft with the brushes assembled thereon, and a driving connection for said driving member.

5. A device of the class described comprising a standard, a driven shaft mounted thereon, a driving member on said shaft located within the standard, a sectional arm movable on said shaft as an axis and having parts overlapping opposite ends of the member to prevent displacement thereof from the shaft, the sections of the arm being separable in a direction transversely of the shaft to release the shaft with the brushes assembled thereon, a brush shaft supported by said arm, and means passing through said arm to drive said brush shaft from said driving member.

6. A device of the class described comprising a sectional arm, having its sections separable laterally, a driving element passing through said arm, a connection driven from said element positioned within the sections of said arm, a brush shaft driven by said element and supported by said arm, and means on said arm holding said brush shaft against displacement.

In testimony whereof I affix my signature.

WALTER D. LEE.
